Walter A. Holden.

UNITED STATES PATENT OFFICE.

HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

HOSE-SUPPORTER BUTTON.

1,290,678.

Specification of Letters Patent.

Patented Jan. 7, 1919.

Application filed April 25, 1916. Serial No. 93,438.

To all whom it may concern:

Be it known that I, HENRY J. STUART, a citizen of the United States, residing at Derby, in the county of New Haven and State of Connecticut, have invented a certain new and useful Improvement in Hose-Supporter Buttons, of which the following is a specification.

My invention relates to loop and button 10 clasps of the style which employ a button having a slotted base plate threaded with tape and its principal object is to provide a button of this character in which the tape is secured to that portion of the base plate 15 between the slots whereby the front of the base plate has its body portion concealed and either the front or back of the base plate, or both, is covered with tape. Another object of my invention is to provide a novel means 20 for securing both extremities of a folded or double-ply tape to the base plate after the tape has been passed over a supporting member on the clasp.

I attain these and other objects of my invention in the device set forth in the following description and accompanying drawings in which like reference characters refer to corresponding parts.

In the drawings:

30 Figure 1 is a front view of a button clasp to which my invention is applied;

Fig. 2, a central longitudinal section taken on line $x-x$ in Fig. 1 but showing the button loop swung forwardly out of engagement with the button;

Fig. 3, detail views of parts of the button;

Figs. 4, 5 and 6, detail views showing the manner in which the tape is threaded, and

Figs. 7 to 9, detail views of modifications.

40 The button clasp generally consists of an attaching link A, a button loop B and a button tape C which carries a button D at its lower extremity. The button loop B, which is connected to the lower side of the attaching link A by a lip E projecting from the upper side thereof, is provided with a bridge F and has the sides of its lower extremity contracted to engage the shank of the button D. With the exception of the button D and 45 the manner of attaching the same to the tape C the device thus far described is one of the common forms of button clasps well known in the art and is merely disclosed herein for

the purpose of showing how my invention is applied. The button D consists of a slotted sheet metal base 2.

Projecting outwardly and riveted to the base 2 is a wire stud 3. The stud 3 is headed to form a convex head 4, which is preferably provided with a downwardly projecting peripheral biting edge 5. The elastic rubber cap or collet 6 is shaped to form a head 7 and a shank 8. The collet 6 is provided with a central aperture 9 having an inside cylindrical wall 10 flared outwardly at its upper extremity. The diameter of the wall 10 is less than that of the head 4 and preferably less than that of the shank of the stud 3. The base 2 of the button is provided with elongated openings 11 and 12. The tape C 70 is slit adjacent to one of its extremities 13 to form an aperture 14. In assembling the parts the extremity 13 of the tape is threaded rearwardly and forwardly through the slots 11 and 12 in the base. The tape is then 75 folded over so that the stud 3 passes through the aperture 14 as shown in Fig. 4. The end 15 of the tape is then passed forwardly through the link A and rearwardly through the loop B and then threaded through the slot 11 as shown in Fig. 5. The end 15 is then passed forwardly through the slot 12 in back of the extremity 13 as shown in Fig. 6. Then the tape is drawn taut and the collet slipped over the stud which passes 80 through the aperture 9 therein, filling the space between the under side of the head of the stud and the front face of the base, and securely holds the apertured extremity of the tape against the base as shown in Figs. 90 1 and 2. In this manner both extremities of the tape are secured to the button after it has been folded around its supporting member on the clasp, thereby eliminating the employment of any outside fastening means, 95 such as stitching. Heretofore in utilizing a double ply tape and a slotted base it has usually been found necessary to fasten the extremities of the tape together by stitches. This operation, however, is eliminated in 100 my device since the tape can be attached both to the supporting member of the clasp and the button, by hand. It should be observed that the apertured extremity of the tape is anchored to the stud during the process of manipulating the opposite end, there-

by making the threading of both ends practicable. It should be further observed that in threading the base in the manner above described its entire front and back faces are lined with tape and that the button is finally assembled after the threading operation is completed.

10 In the modification shown in Fig. 7 I utilize the so called three slot base. The tape is first passed over its supporting member on the clasp and its two extremities brought together. These extremities are then threaded simultaneously through the three slots, as shown, and the stud then 15 passed through the aperture in the tape.

20 My invention, however, is not confined to a double ply tape since I may utilize a single ply tape, a particular instance being shown in Fig. 8 in which the apertured extremity of the tape is passed rearwardly through the lower slot and the stud passed through the aperture. The tape is then threaded rearwardly through the upper slot and forwardly again through the lower slot around 25 the lower edge of the base, then forwardly again through the upper slot and its upper extremity attached to the supporting member of the clasp or other part of the hose supporter in any suitable manner. In this 30 modification it should be noticed that the front of the base is entirely covered with tape.

35 Another instance of the use of a single ply tape is shown in Fig. 9 in which the apertured extremity of the tape is first threaded forwardly through the lower slot and the stud passed through the aperture. The tape is then threaded rearwardly through the upper slot and around the lower 40 end of the base and the stud passed through a second aperture. The tape is then passed rearwardly again through the upper slot and its upper extremity secured to the hose supporter in any suitable manner.

45 While the device above described embodies the preferred form of my invention yet the same is susceptible to such modification as may fairly come within the scope of the appended claims.

50 Having now described my invention what

I claim and desire to protect by Letters Patent is:

1. In a button clasp a base plate provided with slots and a projecting stud, an apertured tape having one of its extremities slipped over said stud and its other extremity passed through said slots, and a recessed elastic member pressed over the stud in front of the tape, whereby both extremities of the tape are secured to the base plate and the front portion of the base plate between the slots is lined with tape. 55

2. In a device of the character described a slotted base plate having its front and rear faces lined with tape, the said tape being folded over a support and having its extremities threaded through said base plate. 60

3. In a button clasp a slotted base plate having its front face portion between the slots lined with tape, the said tape being folded over a support and having its extremities threaded through said base plate, 70 and a button shank mounted on said base plate in front of said tape.

4. In a button clasp a slotted base plate 75 having its front face portion between the slots lined with tape, the said tape being threaded through said plate, a member mounted on said base plate in front of said tape and means for causing said member to 80 coact with said plate to fasten said tape.

5. In a button clasp a base plate provided with a slot, a support and a tape folded over said support, the said tape having both of its extremities passed in the same direction 85 through said slot, and the said base plate being strung so that its front face portion between the slots is lined with tape.

6. In a button clasp a slotted base plate having a stud mounted thereon between 90 the slots, an apertured tape slipped over said stud and passed through said slots, and a recessed elastic member pressed over said stud and against the front of said tape, whereby the tape is secured to that portion 95 of the base plate between the slots.

In testimony whereof I have hereunto set my hand this 31st day of March, 1916.

HENRY J. STUART.
